UNITED STATES PATENT OFFICE

JOHN F. WHITE, OF CHICAGO, ILLINOIS, ASSIGNOR TO HARRY B. STAVER, OF CHICAGO, ILLINOIS

DOG-RACING APPARATUS

Application filed May 21, 1927. Serial No. 193,104.

This invention relates to dog racing tracks, and has to do particularly with improvements in the construction of the same.

The principal object of the invention is to provide an improved dog racing track in which the rail track on which the lure-conveyer travels is built on substantially the same grade as the course, thereby eliminating the time, labor and expense involved in either 10 raising the course above the level of the rail track and the ground or lowering the rail track below the level of the course and the ground.

Another important object is to provide an 15 improved closure for one side of the course which prevents the dogs from leaving the course, which provides a protective mounting for the electricity conductor, and which serves as a support for the stationary parts of a 20 lure-hurdling mechanism, all without obscuring the vision of the spectators when watching the dogs as they run about the course.

Still another object of the invention is to provide an improved lure-hurdling mechanism 25 for use in association with the improved closure for one side of the course.

Other objects and advantages of the invention will be apparent to those skilled in the art upon a full understanding of the construction and arrangement of the improved 30 dog racing track.

One form of the invention is presented herein for the purpose of exemplification, but it will of course be understood that the invention is susceptible of embodiment in other 35 forms coming equally within the scope of the appended claims.

In the drawing:

Fig. 1 is a transverse section through the 40 improved dog racing track, taken at a point adjacent a hurdle in the course;

Fig. 2 is another section, taken on the line 2—2 of Fig. 1; and

Fig. 3 is another section, taken on the line 45 3—3 of Fig. 1.

Dog racing tracks of the type under consideration ordinarily include a course 10 in the form of an oval pathway about twenty feet wide and about a quarter of a mile long, 50 a rail track 11 which extends about the course

along one side of the same, a lure-conveying car 12 mounted on the rail track and propelled by an electric motor about the same at a high rate of speed, and a suitably supported lure 13 carried by the car in a position 55 out over the course.

The dog racing track illustrated in the drawing, while of the type above described, differs in several very material respects from the arrangement ordinarily used. Instead of the course 10 being formed on the top of an elevated embankment, or the rail track 11 being positioned in the bottom of an excavation, either of which constructions is customary in order to bring the level of the 60 course 10 quite a distance above the level of the rail track 11, the course 10 and the rail track 11 are built on substantially the same grade, thereby eliminating the necessity of any filling or excavating in connection with 65 the construction of the dog racing track, which filling and excavating has been found in the past to be one of the biggest items of 70 cost in the construction of dog racing tracks.

The lure conveyer car 12 preferably travels 75 in the open about the inner side of the course 10, and is separated from the course by a fence 14 which is about 3 feet in height. The fence 14, if positioned about the inner as 80 distinguishable from the outer side of the course, is of open-work construction, being 85 preferably covered flush on the side of the same toward the course with a wire network 15 of any suitable fabrication. The motor in the conveyer 12 receives electric current from a third rail 16 by means of a shoe 17 which is connected with the conveyer car by a flexible arm 18, and the third rail 16 is positioned close to the base of the fence 14, where it is both sheltered from the elements and guarded from the dogs by an L-shaped housing 19 which is carried by and forms a part of the fence 14.

If a lure-hurdling mechanism is used, the fence 14 also serves as a support for the stationary parts of such mechanism, the particular mechanism 20 herein disclosed being a part of the present invention and an improvement in certain respects over the lure-hurdling mechanism heretofore developed by 100

me. In the form of mechanism shown, the lure 13 is carried on the downwardly offset end 21 of an arm 22 which is rotatably mounted in an elevated position upon the superstructure 23 of the conveyer car 12.

When the lure 13 approaches a hurdle 24 positioned across the course, the arm 22 is rotated a portion of a revolution to swing the lower end 21 of the arm into a position where-in the lure 13 will clear the top of the hurdle, the turning movement of the arm 22 being effected by engagement of a wheel 25 carried by the upper portion of the arm with an inclined cam 26 carried by the fence in the path of the wheel. The wheel is journaled in the lower end of a bracket 27 which is rigidly secured to the upper portion of the arm 22 on the side of the fence away from the course 10, and, after the wheel has reached the highest point 28 on the cam, the arm 22 is caused to swing quickly back again by means of a spring 29, which spring is secured at one end to the outer end of a bracket 30 on the arm, and at the other end to a bracket 31 on the car. When straight races, as distinguished from hurdle races, are being run the lure-hurdling mechanism may be rendered inoperative by merely withdrawing the spindle pin 32 on which the wheel 25 is journaled, and removing the wheel, the lower end of the bracket 27 being at a sufficient height to clear the high point 28 of the hurdles as the car passes those points.

The lure-hurdling mechanism above described may also be used to remove the lure from the course at the end of a race, it merely being necessary to use a cam on the fence which is high enough to raise the lure above the level of the top of the fence, and a switch in the rail track which will permit the conveyer 12 to be run diagonally away from the fence at the location of such cam, thereby causing the lure to hurdle the fence and disappear from the view of the dogs at the end of a race.

I claim:

1. In a dog racing track, a course for the dogs, a conveyer track positioned alongside the course at substantially the same level, a fence between the conveyer track and the course, an electrically operated lure conveyer on the rail track, a lure arm supported on said conveyer and bent to extend over said fence to near the racing ground, and a lure carried by the lower end of said arm, said arm and the support thereof on said conveyer having sufficient rigidity to hold said lure free of the course.

2. In a dog racing track, an oval-shaped course for the dogs, a rail track positioned along the inner side of the course at substantially the same level, an open-work fence between the rail track and the course, an electrically operated lure conveyer on the rail track, and a substantially rigid arm carried

by the conveyer above the fence and having a downwardly offset lure-supporting portion above the course.

3. In a dog racing track, a course for the dogs, a rail track positioned alongside the course, a fence between the rail track and the course, an electrically operated lure conveyer on the rail track, means carried by the conveyer for supporting a lure above the course, an electrical supply conductor for said conveyer positioned alongside the fence, and a protective housing for the conductor mounted on the fence.

4. In a dog racing track, a course for the dogs, a rail track positioned alongside the course, a fence between the rail track and the course, an electrically operated lure conveyer on the rail track, an arm carried by the conveyer above the fence and having a downwardly offset lure-supporting portion above the course, a cam follower on the arm for turning the same to raise the lure-supporting portion thereof, and a cam mounted on the fence for coaction with the cam follower.

5. In a dog racing track, a course for the dogs, a conveyer track positioned alongside the course, a fence for preventing the dogs on the course from getting on the conveyer track, an electrically operated lure-conveyer on the conveyer track, an arm carried by the conveyer above the fence and a lure carried by the free end of said arm, said arm having a downward bend on the side extending above said course and being of sufficient rigidity and so supported as to hold said lure free of the course.

6. In a dog racing track, a course for the dogs, a conveyer track positioned along the course, an electrically operated lure conveyer on said conveyer track, a lure arm extending from said conveyer over said course, said arm having a downwardly bent portion extending adjacent the surface of said course but free therefrom, a lure carried by said downward portion of said arm, said arm having sufficient rigidity to hold said lure free from said course, and a mounting for said lure arm on said carriage permitting swinging movement of said lure arm around an axis substantially transverse to the course.

7. In a dog racing track, a course for the dogs, a conveyer track positioned alongside said course at substantially the same level, a fence between the conveyer track and the course, an electrically operated lure conveyer on said conveyer track, a lure carried by said conveyer above said course, an electrical supply conductor for said conveyer positioned adjacent the lower end of said fence on the side facing said conveyer track.

In testimony whereof I have hereunto subscribed my name.

JOHN F. WHITE.
